US00D925357S

(12) **United States Design Patent** (10) **Patent No.:** **US D925,357 S**
(45) **Date of Patent:** **** Jul. 20, 2021**

(54) **CONTAINER**

(71) Applicant: **PepsiCo, Inc.**, Purchase, NY (US)

(72) Inventors: **Advait Bhat**, White Plains, NY (US); **Girish Nilkanth Deshpande**, Carmel, NY (US); **Maximiliano Rodriguez**, Hillside, NJ (US); **Benjamin Joseph Tantanella**, New York, NY (US); **Bruno Telesca**, Sandy Hook, CT (US); **Nathan Daniel Grubbs**, West Chester, OH (US); **Ryan Alan Klenke**, St. Henry, OH (US)

(73) Assignee: **PepsiCo, Inc.**, Purchase, NY (US)

(**) Term: **15 Years**

(21) Appl. No.: **29/760,937**

(22) Filed: **Dec. 4, 2020**

Related U.S. Application Data

(63) Continuation of application No. 29/697,241, filed on Jul. 5, 2019, now Pat. No. Des. 904,889.

(51) **LOC (13) Cl.** **09-07**

(57) CLAIM

The ornamental design for a container, as shown and described.

DESCRIPTION

FIG. 1 is a top perspective view of a container showing the claimed design;

FIG. 2 is a another top perspective view thereof;

FIG. 3 is a bottom perspective view thereof;

FIG. 4 is a front view thereof;

FIG. 5 is a rear view thereof;

FIG. 6 is a left side view thereof;

FIG. 7 is a right side view thereof;

FIG. 8 is a top view thereof; and,

FIG. 9 is a bottom view thereof.

The dashed broken lines in the figures show portions of the container that form no part of the claimed design.

The dot-dash broken lines in the figures show boundaries that form no part of the claimed design.

1 Claim, 6 Drawing Sheets
